UNITED STATES PATENT OFFICE.

WILLIAM JOSEPH ANDERSON, OF LIVERPOOL, ENGLAND.

HAT AND HAT-SHIELD.

SPECIFICATION forming part of Letters Patent No. 758,806, dated May 3, 1904.

Application filed April 18, 1903. Serial No. 153,288. (No model.)

To all whom it may concern:

Be it known that I, WILLIAM JOSEPH ANDERSON, draftsman, a subject of the King of England, and a resident of Liverpool, in the county of Lancaster, England, have invented certain new and useful Improvements Connected with Hat Shields or Pads, of which the following is a specification.

This invention has reference to hats and hat shields or pads which are adapted to be placed on the inside of the front portion of a hat—namely, against the leather or like band of same—for the purpose mainly of absorbing perspiration from the forehead of the wearer and preventing soiling of the hat and also insuring greater comfort to the wearer; and my invention has for its object and effect to provide hats with a shield or pad of the kind referred to which is detachably secured or fastened to the hat, the attachment and detachment of which can be easily and quickly effected.

It has also the object and effect to provide a shield or pad of the kind referred to which is effective and neat in appearance and is not liable to get out of shape and will always keep its position in the hat.

The invention will be described with the aid of the accompanying drawings, in which—

Figure 1 is a longitudinal section of a hat to an enlarged scale, showing a pad fitted thereto. Fig. 2 is a face view of the pad, showing it fitted to the interior of the hat; and Fig. 3 is a plan viewed from below of the pad fitted to a hat.

According to this invention the hat shield or pad comprises a piece of felt, flannel, cork, or other suitable material suitably shaped and a piece of textile fabric at the lower edge of same, forming a hinge or jointing-piece adapted to fit on the under side of the brim, to which it is fastened.

Referring to the drawings, *a* represents the felt or other pad, and *b* is a silk or similar textile piece forming the hinge part at the lower edge of same and fastened to it by stitching in any known suitable way. The part *a* fits on the inner lining *c* of the hat—which is generally leather—and extends round the lower

part of the hat-dome *d*, while the hinge part *b* is fitted on and adapted to lie snugly against the part of the brim *e* near the lower edge or part of the dome *d*.

The whole device is conveniently attached to the hat by brass or similar metal fasteners *h* of the type commonly called “paper-fasteners” passed through both the brim and the hinge; but other means of fastening it to the hat may be adopted.

In some cases the hinge part *b* is tubular, and a thin bar or strip of celluloid, xylonite, or other springy material and of the form and radius of the end of the hat to which it is to be applied is inserted in it. This form or construction is shown in the drawings, *i* designating the celluloid, xylonite, or other springy thin strip or bar. The tubular form of the part *b* is made by using a doubled or folded piece of silk or textile material the edges of which are secured together and to the lower edge of the pad part *a* by stitching. The employment of this strip or bar causes the whole device to take its required shape or form and enables the hinge part *b* to adjust itself and lie evenly on the under side of the brim *e*, and to facilitate the device taking this shape and the silk or other textile part *b* to adjust itself freely it is cut on the cross as regards its warp and weft.

A pad as above described provides a construction by which the felt or like part *a* will keep its position in the hat without further attachment and will lie smoothly and evenly on the leather or like lining *c* and will not be disturbed or put out of shape when the hat is taken off or put on the head. The pad part *a* is preferably of considerable thickness—say about one-sixteenth of an inch. In some cases the upper edge of the part *a* may be stiffened or reinforced by a bar or strip of celluloid, xylonite, or other equivalent springy material suitably attached to it. This construction is shown in the drawings, the strip or bar of the springy material being designated *k*. Its use tends to increase the natural tendency referred to of the pad to retain its shape and to lie evenly in position against the inside of the hat.

Having now particularly described and as-

certained the nature of my said invention and in what manner the same is to be performed, I declare that what I claim is—

1. A hat-pad comprising a vertical part *a* adapted to fit inside the hat, a lower horizontal hinge part *b* of textile material, adapted to be fastened to the under side of the brim, said part *b* being tubular and adapted to be fastened to the lower edge of the part *a*; and a spring stiffening-bar *i* inserted in the hinge tubular part *b*; substantially as described.
2. A hat-pad comprising a vertical part *a* adapted to fit inside the hat; a lower horizon-

tal hinge part *b*, adapted to be fastened to the under side of the brim; and a reinforcing-bar ¹⁵ *k* of springy material, secured to the upper edge of the part *a*; the said vertical part being free from connection with the hat, substantially as described.

In witness whereof I have hereunto set my ²⁰ hand in presence of two witnesses.

WILLIAM JOSEPH ANDERSON.
